(57) **CLAIM**

The ornamental design for a nose for a shoe suitable for use in an oil and gas wellbore, as shown and described.

DESCRIPTION

FIG. 1 is front view of a nose for a shoe suitable for use in an oil and gas wellbore showing our new design.

FIG. 2 is left side view of a nose for a shoe suitable for use in an oil and gas wellbore.

FIG. 3 is right side view of a nose for a shoe suitable for use in an oil and gas wellbore.

FIG. 4 is top view of a nose for a shoe suitable for use in an oil and gas wellbore.

FIG. 5 is bottom view of a nose for a shoe suitable for use in an oil and gas wellbore.

FIG. 6 is rear view of a nose for a shoe suitable for use in an oil and gas wellbore; and,

FIG. 7 is perspective view of a nose for a shoe suitable for use in an oil and gas wellbore.

The broken lines are included for the purpose of illustrating portions of the nose for a shoe suitable for use in an oil and gas wellbore and form no part of the claimed design.

1 Claim, 7 Drawing Sheets
